(57) **CLAIM**

The ornamental design for an induction range, as shown and described.

DESCRIPTION

FIG. 1 is a front perspective view of an induction range, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion '8' in FIG. 1; and,

FIG. 9 is an enlarged view of the encircled portion '9' in FIG. 1.

The even-dash broken lines illustrating portions of the induction range form no part of the claimed design. The dot-dot-dash broken lines encircling enlargement portions of the claimed design form no part of the claimed design.

1 Claim, 9 Drawing Sheets
